UNITED STATES PATENT OFFICE.

HERMAN J. SCHULTZ, OF CHICAGO, ILLINOIS, ASSIGNEE TO W. F. HALL PRINTING CO.,
OF CHICAGO, ILLINOIS, A CORPORATION OF ILLINOIS.

UNIVERSAL SHEETING MACHINE.

Application filed March 3, 1922. Serial No. 540,771.

To all whom it may concern:

Be it known that I, HERMAN J. SCHULTZ, a citizen of the United States, residing in the city of Chicago, county of Cook, and 5 State of Illinois, have invented certain new and useful Improvements in Universal Sheeting Machines, of which the following is a specification.

This invention relates to a sheeting machine and refers more particularly to a machine for cutting rolls of paper such as wall paper or other types of roll paper which is printed with designs, into equal length sheets, the novelty of the invention 10 lies in the manual regulation that may be had over the sheet lengths to conform with the variance in the length of the design printed thereon.

Fig. 1 is a side elevation of the machine.
20 Fig. 2 is a side elevation taken from the opposite from Fig. 1.

Fig. 3 is a plan view of the machine.

Figs. 4 and 5 are details of the ratchet device for rotating the cutter showing the 25 ratchet in inoperative and operative positions.

Fig. 6 is a detail taken along the line 6—6 in Fig. 3.

Fig. 7 is a detail taken along the line 30 7—7 in Fig. 3.

Referring to the drawings, 1 is the frame of the machine upon which the mechanism is mounted. At any convenient position in connection with this frame is mounted a 35 motor 2 which drives by means of a belt 3, and pulley 4, a gear 5 through a pinion 6 mounted upon a stub shaft 7. The gear 5 is mounted upon a shaft 6^a upon which is also mounted a roll 7^a over which the 40 paper sheet 8 rides in its travel from the roll 9 to the cutter. The gear 5 is meshed with a second large gear 10 mounted upon the shaft 11 which also carries a sprocket 12. Sprocket 12 through a chain drive 13 rotates the sprocket 14 pinned to the ratchet wheel 15, both of which are loosely mounted upon the shaft 16. An idler pulley 17 serves to keep proper tension upon the chain. Upon the shaft 6 is mounted a 45 pinion 18 which drives through the chains 19 and 20, the shafts 21 and 22 which carry the rolls 23 and 24. These rolls serve the same purpose as the rolls 7, namely, to carry the paper sheet in its travel through the 50 machine.

The paper to be sheeted or cut by means of this mechanism may be a roll of wall paper samples which are printed in regular designs to be mounted in a sample book. Due to the shrinkage of the paper stock 60 in drying and also to the manner in which the design is imposed upon the sheet, there is a decided variance in the length of the design in different portions of the sheet. Consequently, if the sheet was to be cut at 65 regular lengths by the common type of sheeting machine, the positioning of the cut would gradually work away from the proper position at the end of the design 70 into the design itself. For this reason it 75 has become necessary to manually control the positioning of the cut so that each sheeted portion will contain a completed design. The paper coming from the roll 9 is fed onto the machine due to the pressure of the feed rolls 25 which contact with the rolls 7. The rolls 25 are mounted upon supports 26, the pressure between the rolls 25 and 7 being maintained by means of a 80 spring 27 and crank 28 maintaining a rotative pressure upon the pivot shaft 29 which carries the supports 26. Similar feed rolls 30 contact with the bed roll 23 on the opposite end of the machine.

The proper positioning of the cut is effected by causing the fingers 31 which are mounted upon a chain 32 to coincide with the line on which it is desired to cut the paper shown by the dot-dash line 33. If the operator by means of the control handle 34 keeps the finger 31 directly above the line on which he desires the cut to be made, this finger will trip the depending latch 35, which through a series of connections hereinafter described, will properly function the 95 cutter blade 36 to sever the sheet along the desired line 33.

Explaining now the mechanism for controlling the travel of the finger 31. One end of the roll 7 is tapered as shown at 100 37 and on this tapered portion or pulley runs a belt 38 which drives a similar tapered pulley 39 mounted in an opposite manner to the pulley 37. This latter pulley is mounted upon a shaft 40 upon the opposite end of which is mounted a bevel gear 41 meshing with a similar bevel gear 42 carried by the vertical shaft 43. This vertical shaft is pivoted upon the frame by means of the support 44. The bevel gear 105 42 carries the vertical shaft 43.

42 is connected by a web 45 to a pinion 46 which meshes with a larger gear 47 which in turn is meshed with the pinion 48. The gear 47 is mounted upon a stub 49 and the gear 48 on a stub 50, both of which are carried by a frame 51 pivoted on the shaft 43. On the stub shaft 50 is also mounted a sprocket 52 which drives through the chain 32, a sprocket wheel 53 mounted on a similar frame 54 pivoted at 55. A spacer bar 56 holds the frames at a fixed distance apart and moves with the frames in a parallel direction with the sheet. The spacer is cut away as shown at 57 so that the operator 15 may clearly see the position of the fingers 31 which are fastened to the endless chain 32. To keep the finger in coincidence with the line 33 upon which the paper which is to be cut or the line separating the successive design pattern, it is only necessary 20 for the operator to manipulate the handle 34 which is mounted upon a screw threaded shaft 58 threaded in the lug 59, carried by the support 60 which is mounted upon the 25 frame. The opposite end of the threaded shaft 58 is connected by means of an up-standing member 61 to the frame 51 so that when the handle 34 is turned in one direction the frame member 51 pivoted at 30 43 will be moved so that the travel of the finger is retarded and when the handle is turned in the opposite direction the finger on the chain will be moved ahead relative to the travel of the paper sheet. It is understood, of course, that the chain 32 in normal 35 operation is timed to travel at the same rate as the paper sheet. One, two or a plurality of fingers may be attached to the chain 32 so as to make the cuts at any desired 40 intervals on the sheet, and if sheets are to be made of greater length than the endless chain, it is only necessary to change the size of the sprocket 14.

In case the threaded shaft 58 has been 45 turned continuously in one direction to compensate for the variance in a design so that the wheel 34 has reached a position close to the member 59 or in retarding the travel of the finger the frame has been drawn to 50 an opposite extreme position, it is necessary that there be some additional means for increasing or decreasing the rate of travel of the endless chain, so that only small variations either ahead or back shall 55 be compensated by the adjustment effected by the wheel 34. To vary the rate of travel of the endless chain a transverse shaft 63 threaded at 63^a is mounted to bear at one end in the frame 1 and at the other in the 60 central bushing of the web 64. This web is supported by two projecting rods 65 from the side frame of the machine. On the opposite side of the web from that into which the threaded shaft 63 is screwed, are bearing sleeves upon which are mounted the 65

guide pulleys 62. The guide pulleys rotate with the belt 38 as it is driven over the tapered pulleys 37 and 39. To increase the speed of the pulley 39 and consequently the shaft 40 which through a series of connections explained, drives the endless chain 32, it is only necessary to turn the handle 66 so that the belt is moved transversely onto the larger portion of the tapered pulley 37 and the smaller end of the tapered pulley 39. In a similar manner, when the endless chain is traveling at too high a speed or it is desired to reduce the rate of travel of the finger 31 to coincide with the severing line on the wall paper, by turning the handle in the opposite direction so that the belt is moved to a position shown in Fig. 3, the rate of travel of the endless chain is consequently diminished. In Fig. 7 the position of the web 64 is shown in dotted lines, when it has been drawn to a position to increase the speed of the endless chain 38 by means of the screw thread 63^a which is threaded into the central bushing of the web 64. This latter compensation is unnecessary except where the length of the wall paper design units increase in one direction, for when one design unit is short and the next long successively or where a general average of the lengths of the sheets to be cut will be relatively constant, the compensation can be made by means of the regulating handle 34.

Describing now the manner of effecting the severance. The projecting portion of the finger 31 or the lug by means of which the finger is attached to the endless chain, will contact the depending member 35. This member is fixedly mounted upon the transverse shaft 67 and is held in a depending position by means of the spring 68. On the opposite end of the shaft 67 is mounted a trip 70 which fits flush against the flat head portion of the latch 71. The latch is pivoted at 72 upon an upright member 73, the latter being pivoted at 74 in the frame of the machine. An upright catch 75 also mounted on the frame, is engaged by the hook portion 71^a of the latch. Centrally of the upright member 73 is fastened a link 76 which is attached to a slid able trigger 77, the head of which is contacted by a cam 78 fixedly mounted upon the shaft 16. A dog 79 is rotatably mounted upon the shaft 16 and has near its end a pawl 80. This pawl is adapted to engage the teeth of the ratchet wheel 15 when released by the catch 77^a engaging a pin 80^a on the pawl. A spring 81 imposes a constant tension upon the pawl and the spring 82 maintains a constant pull upon the latch 71.

To explain now the operation of the device, when the finger 31 trips the depending member 35 the shaft 67 is caused to rotate so that the trip 70 is thrown into position ¹³⁰

shown in Fig. 5. This raises the latch and releases the hook 71^a of the latch from engagement with the upright catch 75. With the releasing of the latch the upright 5 pivoted bar 73 is moved on its pivot permitting the trigger to slide forward and release the pawl 80. The spring tension upon the pawl immediately engages it with one of the teeth of the ratchet wheel and 10 as the ratchet wheel is pinned to and driven by the sprocket 14, the dog is carried with the ratchet wheel. At 83 on the dog is a pin which projects into the path of the cam so that with its rotation the dog will 15 contact with the cam 78 and carry the cam with it during the remainder of its rotation to a position such as that shown in Fig. 4 where the high portion of the cam contacts and cocks the trigger and releases the pawl 20 from its engagement with a tooth of the ratchet wheel. In recocking the trigger the cam causes the latch to become again engaged on the catch and the trip 70 will resume its position as shown in Fig. 4, at 25 which time the depending member 35 is again in position to be contacted with the finger 31. As the cam 78 and the cutter 36 are fixedly mounted upon the shaft 16, when 30 the cam is rotated by being carried with the dog, the cutter will likewise be rotated to sever the paper sheet at the desired position or along the line 33. It will be understood that the paper sheet has traveled so 35 that the line of severance 33 is directly between the cutting blades 36 and 84 when the blade is rotated to sever the sheet. In a like manner successive sheets of the desired length, are severed from the roll and are fed into a hopper, not shown, at the 40 side of the machine where they are collected and suitably bound.

I claim as my invention:

1. In a sheeting machine, the combination with means for feeding continuously a sheet 45 of material, a cutting means functioning automatically to sever the sheet into predetermined lengths, operating means traveling adjacent the sheet and at substantially the same speed, connections between the operating and cutting means, said operating means manually operable for controlling the speed of said operating means whereby the

sheet may be accurately severed at irregular intervals predetermined by the length of the designs on the sheet. 55

2. In a sheeting machine, the combination with means for feeding a sheet of material, a cutting means functioning automatically to sever the sheet into predetermined lengths, operating means traveling in timed 60 relation with the sheet, connection with the operating means and cutting means whereby the sheet is severed at predetermined intervals dependent upon the speed of the operating means, control means manually 65 operated for regulating the speed of the operating means and thereby severing the sheet conforming with the design thereon.

3. In a sheeting machine, the combination with means for feeding a sheet of material, 70 a cutting means functioning automatically to sever the sheet into predetermined lengths, operating means traveling in timed relation with the sheet, connections between the operating means and cutting means 75 whereby the sheet may be severed at predetermined intervals and means for advancing or retarding the position of the operating means relative the sheet.

4. In a sheeting machine, the combination with means for feeding a sheet of material, a cutting means functioning automatically to sever the sheet into predetermined lengths, operating means traveling in timed relation with the sheet, connections 80 between the operating means and cutting means whereby the sheet may be severed at predetermined intervals and means for increasing or decreasing the relative rate of travel of the operating means and the sheet. 85

5. In a sheeting machine, the combination with means for feeding a sheet of material, a cutting means functioning automatically to sever the sheet into predetermined lengths, operating means traveling adjacent 95 the sheet in timed relation therewith, connections between the operating means and cutting means whereby the sheet may be severed at predetermined intervals, compensating means comprising means for 100 changing the rate of travel of the operating means and means for changing the position of the operating means relative the sheet.

HERMAN J. SCHULTZ.
